UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,126,029.

Specification of Letters Patent.

Patented Jan. 26, 1915.

Application filed November 4, 1912. Serial No. 729,347.

To all whom it may concern:

Be it known that I, DAVID S. KENNEDY, a citizen of the United States, and a resident of Brooklyn, county of Kings, and State of New York, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine or magazines in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine or magazines from which they started.

More particularly, it relates to that form thereof embodying a plurality of magazines, containing matrices of different style or font, and any one of which may be brought into action as desired.

In the accompanying drawings, I have shown my invention in preferred form and by way of example, and as applied to the commercial linotype machine, but obviously many variations and modifications may be made therein, and in its mode of application, without departing from its spirit. Thus, it may be applied to typographical machines of other kinds, such as type setters and type casters, or those which handle type or dies instead of matrices. Generally speaking, I desire it to be understood that I do not limit myself to any specific form or embodiment, except in so far as such limitations are specified in the claims.

Referring to the drawings: Figure 1 is a front view of a portion of a linotype machine embodying my invention; Fig. 2 is a detached perspective view, partly in section and partly broken away, of various constituent parts thereof; Fig. 3 is a sectional view on an enlarged scale, taken substantially on the line 3-3 in Fig. 1; Fig. 4 is a sectional view, taken substantially on the line 4-4 in Fig. 3; Fig. 5 is a detached view, partly broken away, of the magazine selecting keys and coöperating parts; Fig.

6 is a vertical sectional view of the same; Fig. 7 is a sectional view, taken substantially on the line 7-7 in Fig. 1; and Fig. 8 is a vertical sectional view of a modification.

Referring to the drawings, a plurality of stationary superposed magazines A is shown, from which the matrices X are delivered as desired to the front plate F, from which in turn they pass to the other assembling devices, in the manner well understood in the art. The release of the matrices X from the magazines A is controlled by escapements, each comprising a pivoted lever B and pawls B¹, B², which are alternately projected into the magazine channels. The spring B² tends to hold the rearward pawl B¹ in its projected or operative position, but this tendency is resisted and controlled by one of the projections C⁹ on the reed C⁷, which is normally pressed upward by the stronger spring C⁸. It will be noted that a single reed C⁷ is arranged to act on the correspondingly located escapements in each of the superposed magazines, in such manner that when it is moved downward against the force of the spring C⁸, all of the said escapements would be allowed to operate, were it not for the additional mechanism hereinafter referred to.

The reed C⁷ is actuated and controlled by the finger key C, which through the slide C¹ and pawl C² permits the cam-yoke C³ to bring its cam into engagement with the constantly rotated roll C⁴, all in the usual manner. The pivotal movement of the cam-yoke C³ then actuates the reed C⁵ and the pivoted lever C⁶, which engages the projection C¹¹ on the reeds C⁷, so as first to release the escapement levers B, after which the return of the cam-yoke C³ and reed C⁵ permits the spring C⁸ to lift the reed C⁷, and all the parts resume their original condition.

As previously pointed out, the operation of a key C would effect the simultaneous operation of a plurality of escapements, were it not for the other devices now to be described. Each of the magazines A is provided with a transversely disposed rock shaft D, arranged in proximity to the inner ends of the escapement levers B and cut away or recessed to engage the same, as shown in Fig. 3, so that in one position of the rock shaft, the escapement levers B are locked against movement by the springs B², and in

another position thereof are free to be moved thereby, in the manner well understood in the art. It will be apparent, therefore, that matrices may be delivered only from that magazine wherein the escapements are released from the locking influence of the rock shaft.

The rock shafts D are controlled respectively by pivoted key levers E, one for each magazine, the inner end of each lever except that for the upper magazine being connected by a link E¹ to a rock arm E² and connected hub E³, which in turn engages with the corresponding rock shaft D. The key lever E for the upper magazine is connected to the rock shaft D thereof by the link E⁶ and an arm E⁴ and its connected hub E⁵. A spring E¹⁰ connected to the link E¹ acts normally to move the rock shaft D to its operative or locking position, this action being reversed by the key lever E already described. It will be noted that the hubs E³ vary in length to permit the arrangement of the links E¹ side by side, as shown in Fig. 2.

Each of the magazines A (except the upper one) is also provided at its front or delivery end with a pivoted flap F¹, capable of being moved inward to cover the mouth of the magazine, or outward to permit the matrices to be delivered therefrom. The flaps F¹ are preferably formed in sections corresponding to the vertical channel partitions F² (see Fig. 2), so as to permit their free movement with reference thereto. In Fig. 3 the second magazine is shown with its flap opened, and the magazines below it with their flaps closed. The closed flaps below the magazine in operation thus constitute the rear wall of the so-called front-plate F, and serve to guide the matrices properly and to prevent their catching on or being deflected by any projecting portions.

Each of the flaps F¹ is mounted on a rock shaft F³, which is connected by the arm F⁴ and link F⁵ to the rock arm E², in such manner that when the rock shaft D is turned to lock the escapements of a magazine, its flap F¹ will be simultaneously closed; and, conversely, when the rock shaft is operated to unlock the escapements, the flap will be simultaneously opened.

My mechanism also contemplates the interconnection and relation of the several magazines, so that when one is selected and brought into operation, the others will be held out of operation; that is to say, so that when the escapements of one magazine are unlocked and its flap opened, the escapements of the other magazines will be locked and their flaps closed. In the form shown, I obtain this object by devices acting upon and connecting the magazine keys E. These key levers project through individual slots

G¹ in a stationary plate G, each of the said slots being formed with an offset portion or notch G², whereby the key lever may be held in operative position against the force of its spring E¹⁰; and I have also provided means whereby when one of the key levers is actuated so as to bring its corresponding magazine into operation, the other key levers will be freed, so that their connected springs E¹⁰ will act to lock the escapements and close the flaps of the corresponding magazines.

On the rear of the plate G, I mount a vertically movable plate H (see Figs. 5 and 6) normally held in its uppermost position by the spring H¹. Upon the plate H are mounted a series of hooks H³, one for each key lever and in proximity to the slot G¹. These hooks H³ are pivotally mounted at H⁴, and normally pressed inward by springs H⁵, in such manner as to engage in the slot E²⁰ of the corresponding key lever E when the latter is operated, and so that the plate H will then be moved by the key lever. The plate H is also formed with a series of depending arms H², beveled at their lower ends and located in proximity to the slots G¹, in such manner that the downward movement of the plate H causes the arms H² to pass over the locking notches G², and thus to engage any key lever held therein, and by reason of their beveled formation, to move such key lever laterally and thus permit its restoration to normal position by its spring E¹⁰. In other words, assuming a key lever E to be locked in active position by a notch G², when another key is operated, the latter engages its corresponding hook H³ by its slot E²⁰, and the further downward travel of the key moves the plate H and arms H² with it, and releases the locked key lever in the manner previously described.

In Fig. 8 I have shown a simple modification of this locking and releasing mechanism, wherein a transversely movable plate J is employed, the plate being normally urged toward the left by the spring J¹. The plate J is constructed with a series of upwardly extending hooks J², one for each key lever E, and each hook is formed at its upper end with an inclined or beveled surface J³. When a key is depressed and actuated, it moves the plate J laterally to the right, by reason of its engagement with a beveled portion J³, after which the plate is restored by the spring J¹ and the key lever is locked by the hook. When a second key is then operated, it shifts the plate J toward the right, and releases the previously actuated key lever, after which the return movement of the plate in turn locks the second key lever.

It will thus be seen that the devices employed to interconnect the selecting key levers, so that when one is locked in position the others are automatically released, act

indirectly to control the magazines, so that when one is selected and its escapements unlocked and its flap opened, the others are held out of action, in that their escapements are locked and their flaps closed.

Fig. 7 illustrates the mode of connection of the operating hubs E^3 with the locking rock shafts D , the hubs being formed with keys or splines E^{40} so located and arranged that when moved axially in one direction they engage the rock shafts operatively, and when moved in the opposite direction they are freed therefrom, so as to permit the removal of the corresponding magazines in a forward direction and their replacement by others when desired. For instance, the upper hub is shown in inward position and in operative relation to the corresponding rock shaft, and the lower hub in outward position and disengaged from its rock shaft. The connected links are sufficiently flexible laterally to permit this axial adjustment of the hubs.

As previously stated, I have shown my invention in preferred form and by way of example, but obviously many changes and variations therein will suggest themselves to those skilled in the art and still be comprised within its scope.

Having thus described my invention, its construction and mode of operation, what I claim and desire to secure by Letters Patent of the United States is as follows:

1. In a typographical machine, the combination of a plurality of magazines, movable flaps to cover the ends of the magazines, independently movable actuating devices connected to the flaps to effect both their opening and closing, and means whereby the opening movement of one of said actuating devices will cause the closing movement of another of said devices.

2. In a typographical machine, the combination of a plurality of magazines, movable flaps to cover the ends of the magazines, movable actuating devices to effect the opening of said flaps, locking means to hold the flaps in their open position, and means whereby the opening of one of said flaps will effect the release of the locking means and permit the closing of a previously opened flap.

3. In a typographical machine, the combination of a plurality of magazines, movable flaps to cover the ends of the magazines, movable actuating devices to effect the opening of said flaps, locking mechanism for holding the flaps in their open position, springs for closing the flaps when released by the locking means, and means whereby the opening of one of said flaps will effect the release of the locking means and permit the closing of a previously opened flap by its corresponding spring.

4. In a typographical machine, the combi-

nation of a plurality of magazines, each provided with a movable locking device to retain the type or matrices therein, an independently operable actuating device connected to each of the locking devices for moving it to locking and unlocking position, and means whereby the unlocking movement of one of said actuating devices will effect the locking movement of another of said actuating devices.

5. In a typographical machine, the combination of a plurality of magazines, each provided with a movable locking device to retain the type or matrices therein, actuating devices for moving the locking devices to their inactive position, mechanism to hold the said locking devices in their inactive position, and means whereby the movement of one of said locking devices to inactive position will automatically effect the release of the holding mechanism and permit the movement of another locking device from inactive to active position.

6. In a typographical machine, the combination of a plurality of magazines each provided with a movable locking device to retain the type or matrices therein, actuating devices for moving the locking devices to inactive position, mechanism for holding the locking devices in their inactive position, springs for moving the locking devices to active position when released by the holding mechanism, and means whereby the unlocking movement of one of said locking devices will automatically effect the release of another locking device and permit its movement from inactive to active position by its corresponding spring.

7. In a typographical machine, the combination of a plurality of magazines for the type or matrices, movable devices for locking the type or matrices therein, independently operable actuating means for said devices, and positive locking means to hold one of said actuating means in operated position, the said locking means being automatically disengaged by the operation of another actuating means.

8. In a typographical machine comprising a plurality of fonts of type or matrices, the combination of independent operable devices to select one or another font, and positive locking means to hold one of said devices in operated position, the said locking means being automatically disengaged by the operation of another actuating device.

9. In a typographical machine, the combination of a magazine provided with a series of escapements, each comprising two pawls acting alternately to release and arrest the type or matrices therefrom, the lowermost pawl standing normally in the arresting position, springs tending constantly to effect the releasing action of the escapements, a series of spring-actuated members

movable toward the escapements to return them to their normal or arresting position, and means for moving the actuating members away from the escapements to allow their operating springs to act.

10. In a typographical machine, the combination of a series of escapements, springs for effecting the releasing movement of the escapements, a series of spring-actuated members to engage the forward ends of the escapements and movable toward the escapements to return them to and hold them in their normal or arresting position, and means for moving the actuating members away from the escapements to allow their operating springs to act.

11. In a typographical machine, the combination of the escapements B, the actuating devices C⁷ to engage the forward ends of the escapements and hold them in their normal position, the springs C⁸ for urging the actuating devices upwardly, means for depressing said actuating devices against the force of the springs C⁸, and the springs B² to operate the escapements when their actuating devices are depressed.

12. In a typographical machine, the combination of the escapements B, their actuating devices C⁷, the springs C⁸ for urging them upwardly to hold the escapements in their normal position, the further actuating devices C⁵, and the intermediate pivoted levers C⁶ to depress the actuating devices C⁷ when the actuating devices C⁵ are raised, and thus effect the releasing action of the escapements.

13. In a typographical machine, the combination of a plurality of magazines for the

type or matrices, a series of shiftable keys for selecting one or another of the magazines, and locking means to hold one of said keys in its shifted position, the said locking means being automatically released by the operation of another key.

14. In a typographical machine, the combination of a plurality of magazines each provided with a series of escapements, locking devices, one for each magazine, to hold the escapements against action, means for moving one of said locking devices to inactive position independently of the others, and means whereby the movement of a second locking device to inactive position automatically returns the first to active position.

15. In a typographical machine, the combination of a plurality of magazines each provided with a locking device for the type or matrices, a cover flap to close the end of each magazine and connected to the corresponding locking device so as to be opened and closed thereby, means for moving one of said locking devices to inactive position independently of the others, and means whereby the movement of a second locking device to inactive position automatically effects the return of the previously operated locking device to active position and the closing of the connected flap.

In testimony whereof I hereunto set my hand this first day of November, 1912, in the presence of two attesting witnesses.

DAVID S. KENNEDY.
